DESIGN FOR A COMBINED X-RAY TUBE AND TRANSFORMER CASE AND BRACKET

Edward L. Monnot, Canton, Ohio, assignor to
The Weber Dental Manufacturing Company,
Canton, Ohio, a corporation of Ohio

Application June 13, 1936, Serial No. 63,285

Term of patent 7 years

To all whom it may concern:

Be it known that I, Edward L. Monnot, a citizen
of the United States, residing at Canton, in the
county of Stark and State of Ohio, have invented
a new, original, and ornamental Design for a
Combined X-ray Tube and Transformer Case
and Bracket, of which the following is a speci-
fication, reference being had to the accompany-
ing drawing, forming part thereof.

Figure 1 is a perspective view of a combined
X-ray tube and transformer case and bracket,
showing my new design;

Fig. 2 is a side elevation thereof; and
Fig. 3 is a front elevation thereof.

I claim:

The ornamental design for a combined X-ray
tube and transformer case and bracket, as shown.

EDWARD L. MONNOT.
